UNITED STATES PATENT OFFICE.

CHARLES SISSON, OF PROVIDENCE, RHODE ISLAND.

DESIGN FOR A TAPE.

SPECIFICATION forming part of Design No. 20,958, dated July 21, 1891.

Application filed June 20, 1891. Serial No. 396,975. Term of patent 7 years.

To all whom it may concern:

Be it known that I, CHARLES SISSON, a citizen of the United States, residing at Providence, in the county of Providence and State of Rhode Island, have invented and produced a new and original Design for Tapes, of which the following is a specification, reference being had to the accompanying drawing, forming part thereof.

10 The drawing is a view of a piece of tape, showing my design.

The nature of my design is fully represented in the accompanying drawing, to which reference is made; and it consists in groups 15 of short lines arranged longitudinally of the

braid, forming figures extending diagonally on either side of a lesser number of short longitudinal lines connecting such figures, the ends of the threads or lines forming which overlap one another from the bottom to the 20 top to give an indication of a spiral design around the central connecting-lines.

I claim as my invention—

The design for tape fabric, as herein shown and described.

CHARLES SISSON.
